UNITED STATES PATENT OFFICE.

FRANK L. WATSON, OF LOS ANGELES, CALIFORNIA.

PARACHUTE FOR AEROPLANES.

1,332,150.

Specification of Letters Patent. Patented Feb. 24, 1920.

Application filed February 24, 1919. Serial No. 278,710.

To all whom it may concern:

Be it known that I, FRANK L. WATSON, a citizen of the United States, residing at Los Angeles, in the county of Los Angeles and State of California, have invented new and useful Improvements in Parachutes for Aeroplanes, of which the following is a specification.

This invention relates to a parachute construction to retard the descent of aeroplanes and to act as a brake in landing.

The objects of this invention, are first, to provide a parachute construction which does not require any material change in aeroplanes as now constructed; second, to provide a construction which does not interfere with the flight of the aeroplane and is light in weight; third, to provide a construction which is easily manipulated; and fourth, to provide details, whereby simplicity and compactness of structure are secured.

I accomplish these objects by means of the embodiment of my invention illustrated in the accompanying drawing, in which:

25 Figure 1 is a plan view of an aeroplane having a portion of one plane broken away; Fig. 2 is an enlarged section as seen on the line 2—2 of Fig. 1; Fig. 3 is a perspective view of a section through the plane; Fig. 4 is an enlarged section as seen on the line 4—4 of Fig. 1; and Fig. 5 is an enlarged section as seen on the line 5—5 of Fig. 1.

Referring more particularly to the drawings, my invention is shown applied to the upper supporting plane of an aeroplane, the details of the aeroplane construction not being shown as they form no part of my invention. The parachute construction is applied to the upper surface of the plane, and consists of a pliable sheet secured thereto so that it may fill out and stand away from the plane, there being means to hold the sheet flat upon the plane when not in use and to release the sheet when it is desired to use same.

More specifically, 6 indicates the fuselage of the aeroplane and 7 the upper supporting plane. A pliable sheet preferably of canvas or light fabric is indicated by 8. This sheet extends the width of the plane, but has a depth greater than the plane so that under the pressure of air it may belly out as indicated in Fig. 3. The sheet is secured to the plane at its forward and rear edges by means of flexible ropes or cables 9. Secured to the sheet 8 adjacent its rear edge and ad-

jacent the rear edge of the plane is an apron 10. Vent openings 11 are provided at the juncture of the sheet and apron. The forward edge of the sheet is looped to receive a 60 stiffening strip 12. When in collapsed position upon the plane, the rear of the sheet is folded as indicated by 13 in Fig. 2. By referring to Fig. 1 it will be noticed that there is some slack of the cables 9 to permit 65 the parachute sheet to be lifted away from the plane when in use. Snap fasteners 14 secure the edges of the sheet to the outer edge of the plane, providing means for easily detaching the sheet from the plane 70 when air passes thereunder.

In order to insure the front edge of the sheet being held away from the plane, after it has once been released, a construction is provided, which is shown in Fig. 5. Secured to one of the struts 15 is a casing 16, in which slides a bar 17. The upper end of the bar 17 is secured to the forward edge of the sheet. On the rear face of the bar are downwardly inclined teeth 18 adapted to 80 hook over a pin 19 fixed in the casing 16. On the forward face of the bar 17 is a leaf spring 20 the free end of which rests against the casing, thereby pressing the bar 17 to the rear and holding the teeth in engagement 85 with pin 19. It will be noted that bar 17 can be raised by merely pulling upwardly upon it, but the pin 19 prevents the bar from being lowered by downward pressure. In order to lower the bar, it is necessary to 90 force it forwardly against the action of spring 20 so that the ends or tops of the teeth 18 will clear the pin 19. When the sheet 8 is raised or lifted from the plane, the bar 17 rises and the forward edge of the 95 sheet will be held clear of the plane regardless of the continued air pressure underneath the sheet. This provides safety means so that the sheet will not be flattened upon the top of the plane after once having 100 been released and lifted. There are various evolutions of aeroplanes which might cause flattening of the sheet and thereby momentarily place the parachute construction out of operation. The bar 17 prevents 105 this happening. As many bars as found suitable may be used.

In order to hold the forward edge of the sheet against the plane ready for release when desired, a clasping strip 21 is hinged 110 to the entering edge of the plane. This clasping strip overlaps the forward edge of

the sheet, as best shown in Figs. 4 and 5. Means, later described, is provided for holding the clasping strip in position. At appropriate intervals along the upper surface 5 of the plane and adjacent its entering edge are compression springs 22 disposed beneath the forward edge of the sheet, and arranged to give an initial lift to the sheet upon release of the clasping strip 21.

10 The fastening means for the clasping strip is indicated generally by 23 in Fig. 1 and is shown in detail in Fig. 4. A slot 24 is cut in the plane adjacent its forward edge. A bore 25 extending rearwardly communicates with 15 the slot and serves as a guide for the stem of a catch 26. The forward end of the catch 26 is bifurcated, one arm extending above the upper surface of the plane and over the clasping strip 21, the other arm engaging 20 the under surface of the plane. A spiral spring 27 is disposed on the stem of the catch and holds the latter in its forward position. Fastened to the under side of the plane adjacent the slot 24 is a bracket 28 upon which is pivoted a lever 29, one end of 25 which is pivotally attached to the stem of the catch 26. The other end of lever 29 has a cable 30 or any other suitable means attached thereto and leading to a position 30 convenient for its operation by the aviator. It is evident that when the catch is in the position shown in Fig. 4, the forward edge of the parachute sheet is securely held against the plane. Upon moving the catch 35 26 to the rear the clasping strip 21 is released.

Adjacent the rear of the sheet 8 at the position where the upper layer of the fold occurs a stiffening strip 31 is disposed in a 40 pocket, as best seen in Figs. 2 and 3. A clasping strip 32 is hinged to the rear of the plane and a catch 33 to hold the same is provided. This construction is like that on the entering edge. If desired catches 23 and 33 45 may be secured to each other by any well known means so as to be operated from a single control.

The parachute sheet is placed in a collapsed position upon the plane by folding 50 the rear as shown in Fig. 2. The bar 17 is placed in its lower position, clasping strip 21 over the forward end of the sheet, the catch 23 in position to hold the clasping strip, clasping strip 32 over the rear fold 55 with catch 33 holding its clasping strip in position, and the snap fasteners 14 attached. The sheet is now flat against the top of the plane and will not interfere with its operation or release itself due to the pressure of 60 air in the flight of the machine. When it is desired to retard the descent of the machine, due to an accident or any other reason, the aviator manipulates the catch control to move catches 23 and 33 so as to release clasping strips 21 and 32. The compression

springs 22 give the forward edge of the sheet its initial lift throwing the clasping strip 21 into the position shown in Fig. 3. The air now rushes underneath the sheet and fills it out as shown in Fig. 3, so that it acts 70 as a parachute, the snap fasteners releasing the sheet due to pressure. The movement of the sheet to its uppermost position drags the bar 17 upwardly, in which position it locks, thereby holding the forward edge of the 75 sheet so that air can always pass thereunder. The apron 10 is especially useful in nose dives. The rush of air will not tear away the parachute at the rear as air may pass through the vents 11. At the same time resistance 80 is offered and a parachute effect obtained.

In addition to the retarding effect of the parachute in descending, it has a braking effect. Upon release of the parachute during the forward movement of the aeroplane, 85 air resistance is added to the top of the machine. Due to the inertia of the heavier and lower part of the machine, the latter continues to move forward at a greater speed than the top, and the plane tilts presenting a greater plane surface resisting the forward movement of the aeroplane. This will retard the forward movement of the aeroplane, and thereby act as a brake. It is thus seen 90 that the parachute may be used as a brake 95 in landing or to decrease speed, especially where there is danger of a collision.

What I claim is:

1. In an aeroplane, the combination with a supporting plane of a pliable sheet collapsed thereon, means securing said sheet to said plane so that said sheet may fill out and stand away from said plane, means clasping a transverse edge of said sheet to said plane, said means being operable to 100 release said sheet, and means to initially lift the forward edge of said sheet from said plane upon release of said sheet so as to permit the passage of air thereunder.

2. In an aeroplane, the combination with a supporting plane of a pliable sheet collapsed thereon, means securing said sheet to said plane so that said sheet may fill out and stand away from said plane, means clasping a transverse edge of said sheet to said plane, said means being operable to release said sheet, and resilient means tending to lift the forward edge of said sheet from said plane 115 so as to permit the passage of air thereunder.

3. In an aeroplane, the combination with a supporting plane of a pliable sheet collapsed thereon, an apron having openings therein securing said sheet to said plane at the rear, means securing the front edge of 125 said sheet to said plane so that said sheet may fill out and stand away from said plane, and a releasable clasping strip for clasping a transverse edge of said sheet to said plane.

4. In an aeroplane, the combination with 130

a supporting plane, of a pliable sheet collapsed thereon, an apron having openings therein securing said sheet to said plane in the rear, means securing the front edge of 5 said sheet to said plane so that said sheet may fill out and stand away from said plane, a releasable clasping strip for clasping a transverse edge of said sheet to said plane, and resilient means tending to lift the forward edge of said sheet from said plane so 10 as to permit the passage of air hereunder.

5. In an aeroplane, the combination with a supporting plane of a pliable sheet collapsed thereon, means securing said sheet to 15 said plane so that said sheet may fill out and stand away from said plane, a clasping strip hinged to said plane at an edge to clasp a transverse edge of said sheet to said plane, means to releasably hold said strip on said 20 sheet, and resilient means interposed be-

tween the forward edge of said sheet when collapsed on said plane to initially lift said edge and permit the passage of air under said sheet.

6. In an aeroplane, the combination with 25 a supporting plane of a pliable sheet of greater extension than said plane collapsed thereon, cables securing said sheet to said plane so that said sheet may fill out and stand away from said plane, a clasping strip 30 hinged to said plane at an edge to clasp a transverse edge of said sheet to said plane, means to releasably hold said strip on said sheet, springs interposed between the forward edge of said sheet and permit the passage of air thereunder. 35

In witness that I claim the foregoing I have hereunto subscribed my name this 10th day of February, 1919.

FRANK L. WATSON.
